UNITED STATES PATENT OFFICE.

ALLIN W. HEWITT, OF BOGOTA, NEW JERSEY, ASSIGNOR TO UNDERWOOD
TYPEWRITER COMPANY, OF NEW YORK, N. Y., A CORPORATION OF
NEW JERSEY.

TYPE-WRITING MACHINE.

NO. 833,166.

Specification of Letters Patent.

Patented Oct. 16, 1900.

Application filed November 1, 1905. Serial No. 285,435.

To all whom it may concern:

Be it known that I, ALLIN W. HEWITT, a citizen of the United States, residing in Bogota, in the county of Bergen and State of New Jersey, have invented certain new and useful Improvements in Type-Writing Machines, of which the following is a specification.

This invention relates to the paper-controlling mechanism of type-writing machines, and particularly to means for determining mechanically the points at which to insert successive bills or other papers with relation to a single record-sheet—that is, the sheet upon which carbon copies of the bills are made one following another.

One of the main objects of the invention is to simplify the means for determining mechanically how far back to rotate the platen for the insertion of a fresh bill in connection with the same record-sheet.

Another object is to enable any desired depth of margin to be secured at the top of the record-sheet regardless of the depth or extent of the printed matter upon the bill or other paper.

In the accompanying drawings, Figure 1 is a front elevation, partly in section, of a platen-rotating head adapted to be attached to the projecting end of the usual platen-axle. Fig. 2 is a side elevation illustrating one form of clutch which is used between the platen and wheel or member which is seen upon said head. Fig. 3 is a view looking at the left-hand end of the parts seen at Fig. 1. Fig. 4 is a view, partly in section, looking toward the right-hand end of the head seen at Fig. 1. Fig. 5 is a plan of the carriage of the well-known "Underwood" type-writing machine, showing my improvements applied thereto. Fig. 6 illustrates in perspective the parts seen at Fig. 1. Fig. 7 is a sectional elevation showing the parts which are rigid with the hand-wheel seen at Fig. 1.

In said machine the types strike upon the front side of a cylindrical platen 1, which is mounted for revolution by means of an axle 2 in the ends 3 of a platen-frame 4 and is provided with the usual line-spacing devices, including a ratchet-wheel 5 and lever 6 for operating the same. Upon the end of the axle which projects from the end of the platen-frame 4 I secure, by means of a set-screw 7, a head, illustrated in detail at Fig.

1 and comprising a hand-wheel 8, which is fixed by a pin 9 upon the outer end of a shaft 10, the inner end whereof fits over the platen-axle and contains the screw 7, so that the hand-wheel is rigid with the platen-axle and may rotate the platen either forwardly or backwardly.

A wheel 11 is mounted to rotate freely upon the shaft 10, being confined between a shoulder 12, formed on the latter, and a collar 13, fixed upon said shaft 10. Said wheel 11 is used principally when the platen is rotated backwardly for the insertion of a fresh bill. During such backward rotation the wheel is automatically clutched to the platen, and it has a stop whereby both the wheel and the platen are arrested at the proper point for inserting a new bill. The clutch comprises a circular series of teeth or ratchet-wheel 14, formed upon the collar 13, which is secured to the shaft 10 by means of a pin 15, so that said ratchet-wheel must rotate with the platen. A pawl 16 is carried around by the wheel 11 and adapted to engage said ratchet-wheel 14, whereby when the platen is rotated backwardly the wheel 11 is forced to rotate therewith, and when the wheel 11 is rotated forwardly it is capable, through the pawl and ratchet, of rotating the platen. The pawl, which is pressed into the teeth by a spring 17, is in the form of a segment which lies in an annular recess 18, formed in a cup 19, having a hub 20 fitting over the collar and secured thereto by the pin 15. A pin 21 fits in a hole 22, formed in a segment 23, which occupies about one-half of said recess and serves to engage the rear end of the pawl, which is sloping at 24 in such a manner as to tend to force the head of the pawl into the ratchet-teeth, said pawl by reason of its segmental or bow-form having a rocking motion at about the portion 25 of the rim of the cup 19. By a movement of the segment 23 in the opposite direction, so that it engages the head of the pawl, the latter is caused to slip freely over the teeth, as indicated in dotted lines at Fig. 4. Other forms of pawl-and-ratchet mechanism or other kinds of clutches may be used between the revoluble member or wheel 11 and the platen. To said revoluble member 11 I fix rigidly a stop 26 for engaging an arm 27 to arrest backward rotation of the platen, said arm projecting from the end 3 of the platen-

frame in front of the wheel 11. Said stop 26 projects from a disk 28, which is attached by screws 29 to the inner face of the wheel 11 and carries the pin 21 of the pawl-and-ratchet mechanism.

Sometimes the bill to be written contains only a single item and sometimes very many items, so that the platen may be rotated through one or more revolutions by the line-spacing mechanism 6 during the writing of the bill; but I have provided means whereby the platen may be rotated backwardly only a predetermined distance regardless of the position of the platen when such backward rotation begins. To this end I provide upon the pin 11 a stop 30, which engages the under side of the stationary arm 27, thereby to prevent the wheel 11 from rotating forwardly with the platen, so that said wheel is always stationary during the forward rotation of the platen and when rotated backwardly can turn only through the arc, which is predetermined by the relative positions of the stops 26 and 30 upon said wheel.

The stop 30 is formed upon a disk 31, which is revoluble relatively to the wheel; and the latter is provided with a rack 32, consisting of a series of notches curved around the platen-axis. A tooth 33, carried by the disk 31, may engage any of said notches and hold the stop 26 in any desired relation to the stop 30, so as to regulate the extent of the backward rotation of the platen. In order to facilitate rotative adjustment of the disk 31, said tooth 33 is carried upon a spring-plate 34, secured upon the disk by rivets 35. A wedge 36, pivoted at 37 upon the disk 31, may be moved by a finger-piece 38 beneath a nose 39, formed upon the spring-plate 34, so as to withdraw the tooth 33 from the notch 32. The disk 31 may be then rotated independently of the wheel 11, and the handle 38 may be moved to release the spring 34, so that the tooth 33 thereon may spring into engagement with another notch 32. In operation the wheel 11 is turned backwardly until the stop 26 strikes upon the top of the arm 27. Then the finger-piece 38 is moved to release the tooth 33, whereupon the disk 31 is rotated forwardly until the stop 30 strikes the under side of said arm 27. Then a bill is inserted at the back of the platen in the usual manner. Then the platen is rotated forwardly by means of the wheel 11 until the first writing-line on the bill is brought to the printing-point. During such rotation the stop 30 remains stationary against the arm 27. Then the handle 38 is moved to lock the disk 31 to the wheel 11, so that the distance separating the stops 30 and 26 corresponds to the depth of the bill-head—that is, to the extent of the printed matter on the bill-head. The writing of the bill may now proceed line by line, the long record-sheet and the carbon having

been inserted together with the bill. During the writing of the bill the wheel 11 does not rotate; but there is sufficient friction between the same and the contiguous rotating members to hold the stop 30 always against the under side of the arm 27. When the bill is completed, it is withdrawn from the machine without disturbing the carbon and record sheets. The platen is then rotated backwardly by means of the hand-wheel 8, and the clutch mechanism automatically locks the wheel 11 to the shaft 10, so that the wheel revolves backwardly with the platen until both are arrested by the contact of the stop 26 with the top of the arm 27. Then a new bill is inserted and the platen rotated forwardly by the finger-wheel 8 until the first line on the bill reaches the printing-point. In this manner the carbon copies of successive bills are caused to follow one another upon the same record-sheet. The extent of the backward rotation of the platen is determined mechanically, while the extent of the subsequent forward rotation is readily determined by means of the usual front scale provided upon said Underwood machine, so that the operator is not obliged to make any arithmetical calculations and is enabled to handle bills with expedition.

It is sometimes desired to regulate the depth of margin at the top of the record-sheet, especially when there is considerable depth of printed matter upon the bill. To this end I provide upon the disk 31 an index 40, adapted to coöperate with the arm 27. In using this index the bill alone is first inserted and the relation between the stops 30 and 26 determined and the stop 30 locked to the wheel 11, the bill at this time being in position for writing the first line thereon. Before writing, however, the platen is turned backwardly until the index 40 registers with the arm 27, whereupon the carbon and record sheets are introduced between the bill and the platen, the leading edge of the bill being then somewhat in advance of the leading edge of the record-sheet. Then the platen is rotated forwardly until the bill is in position for the first line of writing, which line will fall upon the record-sheet nearer the top thereof than will be the case on the bill. The index 40 is adjustable, so as to secure different depth of margin upon the record-sheet as may be desired by different uses, said index being for this purpose detachably connected by a thumb-screw 41 to the disk 31, the latter having a series of similar threaded holes 42 extending along its outer border to receive said thumb-screw, although any other suitable means for adjusting the index may be provided.

The arm 27 is pivoted at 43 upon a bracket 44, fixed upon the platen end 3, so as to be swung out of the way of the stops 26 and 30 when the machine is to be used for other pur-

poses than billing, the idle position of the arm being indicated in dotted lines at 27^a, Fig. 5. A friction-washer 45 holds the arm wherever set.

5 Variations may be resorted to within the scope of my invention, and portions of my improvements may be used without others.

Having thus described my invention, I claim—

- 10 1. In a type-writing machine, the combination with a revolute platen and mechanism for advancing the platen line by line, of a stop normally idle or ineffective during the rotation of the platen, a finger-wheel, a pawl and ratchet between the finger-wheel and platen, whereby the finger-wheel may rotate the platen in only one direction, and means controlled by said finger-wheel for enabling the platen and finger-wheel to be arrested by 75 said stop.
- 15 2. In a type-writing machine, the combination with a revolute platen and line-spacing devices therefor, of a finger-wheel, and a pawl and ratchet between the finger-wheel and platen, whereby the finger-wheel may rotate the platen in one direction only, and a stop for limiting the revolution of said platen by said finger-wheel, adjustable means being provided for varying the extent of rotation 80 of the platen by said finger-wheel before arrested by said stop.
- 20 3. In a type-writing machine, the combination with a revolute platen and mechanism for advancing the platen line by line, of a stop normally idle or ineffective during the rotation of the platen, a revolute member normally disconnected from the platen, and a pawl-and-ratchet mechanism for connecting said revolute member to the platen at will 85 during only the backward rotation of the latter; said revolute member having means to coöperate with said stop to arrest only the backward revolution of the platen.
- 25 4. In a type-writing machine, the combination with a revolute platen and line-spacing devices therefor, of means, including a pawl-and-ratchet mechanism, for mechanically limiting the backward revolution of the platen, means being provided for varying the 90 are through which the platen may be turned back before being arrested.
- 30 5. In a type-writing machine, the combination with a revolute platen and line-spacing devices therefor, of a finger-wheel, means for enabling said finger-wheel to rotate said platen forward, a revolute member, a clutch between said revolute member and said platen or finger-wheel, said clutch being effective only during the backward rotation 95 of the platen, and a stop coöperating with said clutch member for limiting the backward rotation of the platen.
- 35 6. In a type-writing machine, the combination with a revolute platen and line-spacing devices therefor, of a finger-wheel, means for enabling said finger-wheel to rotate said platen forwardly, a revolute member, a clutch between said revolute member and said platen or finger-wheel, said clutch being effective only during the backward rotation 100 of the platen, and a stop coöperating with said clutch member for limiting the backward rotation of the platen.
- 40 7. In a type-writing machine, the combination with a revolute platen and mechanism for advancing the platen line by line, of means normally disconnected from the platen but connectible thereto at will, for turning the platen in only backward direction from any point to which it may have been advanced by said line-spacing mechanism, and for arresting the platen after its backward 105 rotation through a predetermined number of line-spaces.
- 45 8. In a type-writing machine, the combination with a revolute platen and mechanism for advancing the platen line by line, of means normally disconnected from the platen but connectible thereto at will, for turning the platen in only backward direction from any point to which it may have been advanced by said line-spacing mechanism, and for arresting the platen after its backward rotation 110 through a predetermined number of line-spaces; adjustable means being provided for enabling such backward stroke of the platen to be varied.
- 50 9. In a type-writing machine, the combination with a revolute platen and line-spacing devices therefor, of a revolute member, a clutch between said revolute member and the platen, said clutch effective only during the backward rotation of the platen, means detaining said revolute member stationary 115 in a predetermined position during the forward rotation of said platen and said revolute member.
- 55 10. In a type-writing machine, the combination with a revolute platen and line-spacing devices therefor, of a revolute member, a clutch between said revolute member and the platen, said clutch effective only during the backward rotation of the platen, means detaining said revolute member stationary in a predetermined position during the forward rotation of said platen and said revolute member, provision being made for effecting relative adjustment of said parts so as to vary the extent of the backward stroke of the platen and revolute member before arrested 120 by said stop.
- 60 11. In a type-writing machine, the combination with a revolute platen and line-spacing devices therefor, of a revolute member, forward and back stops for limiting the rotation of said revolute member, and a clutch between said platen and said revolute mem- 125
- 65 ber.

ber and effective only when the platen is turning backwardly.

12. In a type-writing machine, the combination with a revoluble platen and line-spacing devices therefor, of a revoluble member, forward and back stops for limiting the rotation of said revoluble member, and a clutch between said platen and said revoluble member and effective only when the platen is turning backwardly; means being provided for effecting relative adjustment of said stops so as to vary the extent of backward stroke of the platen.

13. In a type-writing machine, the combination with a revoluble platen and line-spacing devices therefor, of a revoluble member, relatively adjustable stops for limiting the strokes thereof, and a pawl-and-ratchet mechanism between said revoluble member and said platen.

14. In a type-writing machine, the combination with a revoluble platen and line-spacing devices therefor, of a revoluble member, relatively adjustable stops for limiting the strokes thereof, and a pawl-and-ratchet mechanism between said revoluble member and said platen, and effective only when the platen is turning backwardly.

15. In a type-writing machine, the combination with a revoluble platen and line-spacing devices therefor, of a revoluble member having a rack, a stop adjustable upon said revoluble member and having a part to coöperate with said rack to hold the stops where adjusted, and a clutch between said revoluble member and said platen, for enabling the latter to be arrested by means of said stop.

16. In a type-writing machine, the combination with a revoluble platen and line-spacing devices therefor, of a revoluble member having a rack, a stop adjustable upon said revoluble member and having a part to coöperate with said rack to hold the stops where adjusted, and a clutch between said revoluble member and said platen, for enabling the latter to be arrested by means of said stop when the platen is rotating backwardly; means being provided upon said rotating member for holding it stationary in a predetermined position while the platen is rotating forwardly.

17. In a type-writing machine, the combination with a revoluble platen, and line-spacing mechanism therefor, of a member revoluble about the platen-axis, a curved rack upon said revoluble member, a stop adjustable around said revoluble member and having a tooth to engage said rack, means for holding said tooth out of said rack, a stop fixed upon said revoluble member, and means for enabling only the backward rotation of

said platen to be arrested by one of said stops, and for enabling the other of said stops to hold said revoluble member stationary during only the forward rotation of the platen.

18. In a type-writing machine, the combination with a revoluble platen, of means including a member revoluble with the platen and a stop for arresting both the platen and the revoluble member; for determining mechanically the extent of movement of the platen for bringing the first line on a bill or the like to the printing-point, of independent means for gaging the top margin of a record-sheet inserted with the bill.

19. In a type-writing machine, the combination with a revoluble platen, of means including a member revoluble with the platen and a stop for arresting both the platen and the revoluble member, for determining mechanically the extent of movement of the platen for bringing the first line on a bill or the like to the printing-point, of independent means for gaging the top margin of a record-sheet inserted with the bill; said gaging means including a member adjustable so as to secure different depths of margin on the record-sheet.

20. In a type-writing machine, the combination with a revoluble platen, and line-spacing mechanism therefor, of a platen-frame, a member revoluble about the platen-axis and having a rack concentric with said axis, a stop adjustable about said axis and having a tooth to engage said rack, an index rigid with said stop, a stop rigid upon said revoluble member, a stop upon said platen-frame to coöperate with both said index and said stops, and a clutch between said revoluble member and said platen and effective to turn said revoluble member only during the backward rotation of the platen.

21. In a type-writing machine, the combination with a revoluble platen, and line-spacing mechanism therefor, of a platen-frame, a member revoluble about the platen-axis and having a rack concentric with said axis, a stop adjustable about said axis and having a tooth to engage said rack, an index rigid with said stop, a stop rigid upon said revoluble member, a stop upon said platen-frame to coöperate with both said index and said platen and effective to turn said revoluble member only during the backward rotation of the platen; said index being adjustable about said axis for securing different depths of a top margin upon the record-sheet.
